(57) **CLAIM**

The ornamental design for a bottle, as shown and described.

DESCRIPTION

FIG. 1 is a front perspective view of a bottle showing my new design;

FIG. 2 is a front view of the bottle shown in FIG. 1;

FIG. 3 is a rear view of the bottle shown in FIG. 1;

FIG. 4 is a side view of the bottle shown in FIG. 1;

FIG. 5 is another side view of the bottle shown in FIG. 1;

FIG. 6 is a top view of the bottle shown in FIG. 1;

FIG. 7 is a bottom view of the bottle shown in FIG. 1;

FIG. 8 is a perspective view of an alternative embodiment of the bottle shown in FIG. 1;

FIG. 9 is a front view of the bottle shown in FIG. 8;

FIG. 10 is a rear view of the bottle shown in FIG. 8;

FIG. 11 is a side view of the bottle shown in FIG. 8;

FIG. 12 is another side view of the bottle shown in FIG. 8;

FIG. 13 is a top view of the bottle shown in FIG. 8; and,

FIG. 14 is a bottom view of the bottle shown in FIG. 8.

The broken line showing of portions of the bottle top and bottom portion in the relevant drawings shown unclaimed subject matter for the design in those drawings.
